US00D965955S

(12) United States Design Patent (10) Patent No.: US D965,955 S
Wu (45) Date of Patent: * Oct. 11, 2022

(54) WOMAN SEXY NIGHTDRESS

(71) Applicant: SHENZHEN SAILVAN NETWORK TECHNOLOGY CO., LTD., Shenzhen (CN)

(72) Inventor: Jianxun Wu, Shenzhen (CN)

() Term: 15 Years

(21) Appl. No.: 29/727,980

(22) Filed: Mar. 15, 2020

(51) LOC (13) Cl. 02-01

(52) U.S. Cl. USPC D2/720

(58) Field of Classification Search

Primary Examiner — Michelle E. Wilson

Assistant Examiner — Clese Moore, Jr.

(57) CLAIM

The ornamental design for a woman sexy nightdress, as shown and described.

DESCRIPTION

FIG. 1 is a front, left side, top perspective view of a woman sexy nightdress showing my new design;

FIG. 2 is a front elevational view thereof;

FIG. 3 is a rear elevational view thereof;

FIG. 4 is a right side elevational view thereof; and,

FIG. 5 is a left side elevational view thereof.

The broken lines depict environment that forms no part of the claimed design for the woman sexy nightdress.

1 Claim, 5 Drawing Sheets
